UNITED STATES PATENT OFFICE

WILBERT NELSON ELLIOTT AND WINFORD GLADSTONE MILNE, OF HAMILTON, ONTARIO, CANADA, ASSIGNORS TO N. SLATER COMPANY, OF HAMILTON, ONTARIO, CANADA, A CORPORATION OF CANADA

EYE FOR ANCHOR RODS, EYE BOLTS, AND THE LIKE

Application filed May 25, 1931, Serial No. 539,981, and in Canada June 17, 1930.

Our invention relates to improvements in eyes for anchor rods, eye bolts and the like, and is particularly constructed for the reception of guy wires.

5 The object of our invention is to construct an eye incorporating a rotatable member which will rotate as the guy wire is drawn therearound in being tightened up, and a further object of our invention is to provide 10 means for locking the rotatable member against rotation when the guy wire is tightened and secured so that any possible slippage of the guy wire after it is tightened has to overcome friction between the locked rotatable member and the guy wire loop extending therearound.

Another and particular object of our invention is to furnish a clamping bolt upon 20 which the rotatable member is freely mounted and which when tightened up clamps the rotatable member against one leg of the bifid portion of the eye in which it is mounted to lock such rotatable member against rotation.

Our invention consists of an eye of the 25 character described, constructed and arranged all as hereinafter more particularly described and illustrated in the accompanying drawings in which:—

Fig. 1 is a front elevational view of the 30 upper portion of an anchor rod showing our eye formed upon the end thereof, and the guy wire loop extending therethrough.

Fig. 2 is a side elevational view of the construction shown in Fig. 1, a portion of the 35 guy wire loop only being shown.

Fig. 3 is a perspective view of a fragmentary portion of the leg of the bifid portion of our eye against which the rotatable member is clamped.

40 Fig. 4 is a similar view to Fig. 3, showing a fragmentary portion of the other leg of the bifid portion.

Fig. 5 is a perspective view of the bolt upon 45 which the rotatable member is mounted, and

Fig. 6 is a perspective view of the rotatable member or spool.

Like characters of reference indicate corresponding parts in the different views in the drawings.

Our eye which is formed upon the end of an anchor rod or eye bolt 1 consists of a bifid portion formed upon the end of the rod, either integrally as shown, or as a separate member connected thereto in any suitable manner, and 2 is a spool rotatably mounted between the legs 3 and 4 of the bifid portion in the vicinity of their outer ends. The spool 2 is formed with a guy wire receiving groove 5 around which the guy wire 6 extends, the 55 groove being substantially semi-circular, and of slightly larger diameter than the diameter of the guy wire which it is adapted to receive, it being understood that the guy wire is made up of a plurality of strands as shown 60 in the drawings.

The spool 2 is formed with a central orifice 7 and freely mounted upon a bolt 8 extending across the bifid portion through orifices 9 and 10 in the legs 3 and 4 respectively. The 70 bolt 8 is formed with a shoulder 11 of greater length than the diameter of the bolt and formed between the inner end of the bolt and its head 12. The shoulder has round ends and is contained within the orifice 9 in the 75 leg 3, such orifice being of the same shape as the shoulder so that the bolt is held against rotation.

Upon reference to Fig. 2 it will be seen that the spool 2 is of less width than the distance 80 between the legs 3 and 4 between which it is positioned, and also the shoulder 11 is of a greater thickness than the thickness of the leg 3, so that it projects inwardly beyond the inner face of such leg to bear against the adjacent side of the spool when the nut 13 is tightened up.

The side faces 14 of the spool and the inner 85 face 15 of the leg 4 are each radially serrated so that when either of the serrated faces of

the spool are drawn into contact with the serrated face of the leg the spool will be retained against rotation.

When the guy wire passing over the spool is being tightened up the nut 13 on the bolt 8 is loose and the bolt knocked a slight distance towards the leg 3 so that the shoulder 11 does not bear tightly against the adjacent side of the spool to press the other side of the spool against the serrated face 15. In this way the spool is free upon the bolt 8 and will rotate as the guy wire is tightened up.

The guy wire is drawn taut by exerting a pull upon its free end which has been passed around the spool and as such spool is free to rotate there is no frictional drag between the wire and the spool, as is the case in all other types of eye construction wherein the wire receiving face is permanently stationary.

When the guy wire is drawn to the required tautness, the end of the wire is secured to the main portion by any suitable clamp 16 and the nut 13 upon the bolt 8 tightened up so that the shoulder 11 upon the bolt 8 engages the side of the spool and draws such spool into clamping engagement with the serrated face 15 of the leg 4. In this manner the spool is rigidly held against rotation. As the groove 5 in the spool is of semi-circular cross section and of approximately the same diameter as the guy wire, it will be understood that in drawing the guy wire taut around the freely rotatable spool that there is little possibility of the stranded wire becoming flattened or distorted with the consequent uneven distribution of strains upon the inside and outside strands, as is very often the case in drawing a stranded wire around a circular rigid face.

By permitting the spool to rotate when the guy wire is being tightened up the galvanizing or other protective coating upon the spool will not be scraped off as the wire will not drag along the face of the spool during the tightening operation.

If it is desired to reset or retighten the wire at any time it is only necessary to loosen the clamp 16 and then to slacken the nut 13 and knock the bolt slightly in the direction of the leg 3, so that the bolt shoulder 11 does not retain the spool in close contact with the serrated face 15.

In cases where it is desirable to have two or more guy wires extending from one eye the bifid portion is formed of a greater width, so that the legs 3 and 4 permit the free insertion of the desired number of spools therebetween, a longer bolt 8 of course being furnished. When the nut 13 on the bolt 8 is tightened up the shoulder 11 bears against the outside face of the adjacent spool, drawing the abutting serrated spool faces together and also the face of the spool adjacent to the leg 4 into engagement with the ser-

rated face 15 of such leg so that the whole assembly is locked against rotation.

From the foregoing description it will be seen that we have devised an eye for anchor rods, eye bolts and the like in which there is no distortion of the spool supporting bifid portion when the spool is clamped thereto, so that the spool may be at any time released to freely rotate, and although we have shown and described a particular embodiment of our invention wherein we have shown a particular construction for rotatably mounting our eye and also for securing such eye against undesired rotation, it is to be understood that we can make such changes and alterations as we may from time to time deem necessary without departing from the spirit of our invention as set forth in the appended claims.

What we claim as our invention is:—

1. An eye for anchor rods and the like comprising a bifid portion carried upon the end of the rod, a cable receiving spool rotatably contained within the bifid portion, and releasable means for locking the spool against rotation. 85

2. An eye for anchor rods and the like comprising a bifid portion carried upon the end of the rod, a cable receiving spool rotatably contained within the bifid portion, and releasable means for drawing the spool and bifid portion into engagement to retain the spool against rotation. 95

3. An eye for anchor rods and the like comprising a bifid portion carried upon the end of the rod, a cable receiving spool rotatably contained within the bifid portion, and releasable means for drawing the spool into engagement with one of the legs of the bifid portion to hold the spool against rotation. 100

4. An eye for anchor rods and the like comprising a bifid portion carried upon the end of the rod, a cable receiving spool rotatably contained within the bifid portion, a bolt extending across the bifid portion and upon which the spool is freely mounted, and means carried upon the portion of the bolt extending between the legs of the bifid portion for engaging and moving the spool into engagement with one of the legs of the bifid portion. 110

5. An eye for anchor rods and the like comprising a bifid portion carried upon the end of the rod, a cable receiving spool rotatably contained within the bifid portion, a bolt extending across the bifid portion and upon which the spool is freely mounted, and a shoulder formed upon the head end of the bolt and projecting through an orifice in one of the legs of the bifid portion to bear against the spool. 115

6. An eye for anchor rods and the like comprising a bifid portion carried upon the end of the rod, serrations upon the inner face of one of the legs of the bifid portion, a cable receiving spool contained within the bifid

portion, the thickness of said spool being less than the distance between the inner faces of the legs of the bifid portion, serrations upon the side face of the spool adjacent the serrated face of the leg, a bolt extending across the bifid portion and upon which the spool is mounted, and a shoulder formed upon the head end of the bolt and projecting through an orifice in the other leg of the bifid portion to bear against the spool and move it into engagement with the serrated face of the other leg when the bolt is tightened.
